(57) **CLAIM**

The ornamental design for a bath transfer bench, as shown and described.

DESCRIPTION

FIG. 1 is a front perspective view of my design comprising a bath transfer bench;

FIG. 2 is a front side orthogonal view of my design; FIGS. 3 and 4 are left and right side orthogonal views of my design; and,

FIG. 5 is a top orthogonal view of my design.

The dashed lines in FIGS. 1-4 represent environmental structure and form no part of the claimed design.

All other surface(s) or portion(s) of the embodiments of my design not shown in the figures or otherwise described in the specification form no part of the claimed design.

1 Claim, 5 Drawing Sheets(56)
